UNITED STATES PATENT OFFICE.

PETER J. ZEHNDER, OF DAYTON, OHIO.

DESIGN FOR A LOBSTER-CRACKER.

40,611.

Specification for Design.

Patented Apr. 5, 1910.

Application filed January 27, 1909. Serial No. 474,634. Term of patent 7 years.

To all whom it may concern:

Be it known that I, PETER J. ZEHNDER, a citizen of the United States, residing at Dayton, in the county of Montgomery and State of Ohio, have invented a new, original, and ornamental Design for Lobster-Crackers, of which the following is a specification, reference being had to the accompanying drawings, forming part thereof.

Figure 1 is a plan view of a lobster

cracker, showing my new design. Fig. 2 is a side elevation of the same.

I claim—

The ornamental design for a lobster cracker, as shown.

PETER J. ZEHNDER.
